UNITED STATES PATENT OFFICE.

WILLIAM ARTHUR TOOKE, OF MONTREAL, QUEBEC, CANADA.

COLLAR.

Application filed June 14, 1926. Serial No. 115,953.

This invention relates to improvements in collars, particularly to fold collars of the semi-soft type, and the objects of the invention are to produce a smooth line of folds to be comfortable on the neck of the wearer, to improve the shape of the collar and cause it to attain such shape when folded, to effect economy in the processes of manufacturing the collar and generally to improve and simplify the construction of the same.

The invention consists essentially of the improved collar hereinafter described in detail in the accompanying specification and drawings.

15 In the drawings:

Figure 1 is a perspective view of the collar embodying the present invention, one point of the folded portion being turned upwardly to expose the underside thereof,

20 Figure 2 is a detail plan showing the bent body portion and the end tabs before they are completely assembled,

Figure 3 is a section on the line 3—3 of Figure 2 when the parts are assembled in 25 their final relation,

Figure 4 is a section on the line 4—4 of Figure 2 with the parts in their final assembled position.

Referring more particularly to the drawings, in which like characters of reference indicate corresponding parts in each figure, A indicates the body portion of the collar made of a relatively heavy woven fabric of such thickness or body as to give the proper set and form to the collar in use. This body portion is folded whereby the inner portion 10 constitutes part of the band, while the outer portion 11 forms the folded-over or exterior portion of the collar. The body portion is suitably cut to take any form that may

40 be desired and of any convenient depth. It is preferably formed around all its edges by an inturned portion 12 held in place by stitching 13 of which two parallel rows are shown. The inturned portion of the ends

45 of the collar, it will be noted, extends in continuous strips throughout the whole width thereof, so that added reinforcement is given to the collar at this point, and the desired set to this part of the folded-over portion of the collar is imparted; in fact throughout the construction all edges of the members are formed with inturned reinforcements.

50 The inner portion of the member A which constitutes in part the band of the collar is re-enforced by a band member B secured to

the inner portion of the member A by suitable stitching 14. This member is formed of fabric of suitable thickness and body for the purpose required and to correspond with the general design of the collar. It will be observed that the member B, being between the folded portions of the member A, will give a set to the line of fold and, by suitably cutting the upper edge of the member B, an accurate set may be given to the line of fold and to the collar itself. The opposite members 15 and 16 of the member B are extended beyond the member A to constitute connecting flaps and are formed with suitable buttonholes 17. The cut edges of the member B are preferably re-enforced by turning such edges inwardly and retaining them in such position by a line of suitable stitching 18.

In order to cover the unprotected inturned edges on the projecting flaps 15 and 16 and also to give additional strength and finish to the collar, I provide supplementary flaps or members C which are stitched to the member A on the inner side of the collar and are of a shape corresponding with the projecting flaps 15 and 16 to which the members C are secured by suitable stitches. The cut edges of the member C are preferably turned to form an edge re-enforcement 19, being retained in such position by suitable stitching. When the parts are assembled together, the line of stitching around the periphery of the member C will serve to retain the inturned edges in position and to secure the member C to the projecting tabs 15 and 16 of the member B and to the member C. In this way a firm and finished edge will be provided on the collar.

It will be seen further that the collar is composed of only four pieces, each of a character that may be readily cut and formed, and that they may be assembled together in a simple way.

In making the collar the member A is first formed with the inturned edges, the member B is formed with its inturned edges and the member C with its inturned edges. The inturned edges of the member A are stitched down, the parts are placed in assembled relation, and the line of stitching formed which connects the member A with the member B, this same line of stitching connecting the member B with the member C and serving not only to connect the said members but to retain the inturned edges on the members

B and C in place. A final cross line of stitching 20 is then added to retain the member C in position.

As many changes could be made in the above construction, and many apparently widely different embodiments of my invention, within the scope of the claims, constructed without departing from the spirit or scope thereof, it is intended that all matter contained in the accompanying specification and drawings shall be interpreted as illustrative and not in a limiting sense.

What I claim as my invention is:

1. A fold-collar comprising a body portion forming a band and folded-over portion for the collar, a band member secured between said band portion and the folded-over portion, said band member being formed with projecting ends, tabs secured to the project-

ing ends and the body portion of the collar, 20 and an inturned reinforcement throughout the entire edge of each member of the collar.

2. A fold-collar comprising a body portion forming a band and folded-over portion for the collar, inturned edges at the ends thereof extending over the band and folded-over portion, and an inturned edge for the folded-over portion, a band member attached to said body portion between the band portion and the folded-over portion thereof, designed to give set to the collar, the said band portion formed with projecting ends, and tabs connected to said projecting ends and the body portion of the collar.

In witness whereof I have hereunto set my hand.

WILLIAM ARTHUR TOOKE.
